SPRING WINDING MACHINE

Peter M. Sampatacos, Torrington, and Edward E. Franks, Jr., Litchfield, Conn., assignors to The Torrington Manufacturing Company, Torrington, Conn., a corporation of Connecticut

Application April 2, 1951, Serial No. 218,792

4 Claims. (Cl. 140—82)

The invention relates to a machine for coiling or winding lengths of wire to form springs, and it relates more particularly to a machine of the type wherein the lengths of wire are successively connected with a rotatable arbor and are coiled or wound thereon. The invention relates more particularly to a machine of the gear segment type. The present invention incorporates some of the features disclosed in our copending application for Spring Winding Machine, Serial No. 218,791, filed on even date herewith, now Patent No. 2,697,470, dated September 24, 1954.

One object of the invention is to provide a machine of the segment type having a clutch and a brake, more particularly an electromagnetic clutch and an electromagnetic brake, for driving and stopping the spindle and including means for disengaging the brake and engaging the clutch to effect rotation of the arbor carrying spindle in the winding direction during the entire movement of the segment in one direction and for disengaging the clutch and engaging the brake during movement of the segment in the reverse direction so as to stop the spindle when it has rotated in the reverse direction at least approximately to its starting position.

Another object of the invention is to provide a machine having the characteristics last above-stated, and also having additional means for accurately locating the spindle in its starting position at the beginning of each rotation thereof in the winding direction.

Another object of the invention is to provide a machine of the type specified having two spindles and having a clutch and a brake for each spindle operable as above stated.

Another object of the invention is to provide a machine of the type specified having two spindles and a clutch and a brake for each of them, and also having means for so operating the clutches and brakes that the spindles are operable alternately, each spindle being idle while the other is operating.

Another object of the invention is to provide a machine of the type specified having two spindles and a clutch and a brake for each of them and constructed and arranged so that the spindles can be operated in unison or can be operated alternately as above stated.

Other objects of the invention are to provide various details of mechanical structure and of electrical arrangement whereby the foregoing more general objects are attained.

Still other objects of the invention will be apparent from the drawings and from the following description and claims.

In the drawings we have shown in detail a preferred embodiment of the invention, but it will be understood that various changes may be made from the construction shown, and that the drawings are not to be construed as defining or limiting the scope of the invention, the claims forming a part of this specification being relied upon for that purpose.

2

Of the drawings:

Fig. 1 is a perspective view showing a spring wire bent to the form in which it is supplied to a machine embodying the invention, this view showing the spring in position for winding by the machine, portions of which are shown schematically.

Fig. 2 is a perspective view similar to Fig. 1 but showing the spring after it has been wound.

Fig. 3 is a plan view of a machine embodying the invention.

Fig. 4 is a front view.

Fig. 5 is an enlarged generally vertical sectional view taken along the line 5—5 of Fig. 4, with the gear segment in its central position.

Fig. 6 is a developed sectional view taken along the line 6—6 of Fig. 4.

Fig. 7 is an enlarged fragmentary vertical sectional view taken along the line 7—7 of Fig. 4.

Fig. 8 is an end view of the parts shown in Fig. 7, or a rear view of the same parts as shown in the lower left corner of Fig. 4.

Fig. 9 is a horizontal sectional view taken along the line 9—9 of Fig. 7.

Fig. 10 is an enlarged fragmentary vertical sectional view taken along the line 10—10 of Fig. 3.

Fig. 11 is an enlarged fragmentary front view of some of the parts directly associated with the spindle.

Fig. 12 is a view showing in different positions some of the parts shown in Fig. 11.

Fig. 13 is a diagram showing the electrical control for the machine.

Figs. 14 to 18 are schematic views illustrating the movements of some of the parts of the machine.

A machine embodying the invention may be used for coiling or winding springs of various types. One form of spring that may be wound is shown in Fig. 2 of the drawings, this spring having two similar coils. The spring as shown in Fig. 2 is to be regarded as merely illustrative, the invention not being limited to machines for coiling or winding such a spring. The machine is shown in particularly adapted for the winding or coiling of pieces or lengths of wire which are cut and which may be partly formed before being supplied to the machine. However, the invention is not limited to a machine for the coiling or winding of previously cut and formed lengths of wire.

Fig. 1 shows a wire 10 bent to the shape in which it is supplied to the machine in order to produce the spring shown in Fig. 2. The wire 10 has a generally "hairpin" shape, with two side portions 12, 12 and a transverse connection portion 14. The wire 10 is shown as engaged with a dog 16 having splined engagement with a rotatable arbor 18 carried by the rotatable spindle of the machine. The dog 16 is freely engageable with or disengageable from the arbor 18 by endwise movement and the splining is such that the dog can be engaged in only one position. The side portions 12, 12 of the wire are engaged with a stationary stud 20 to prevent rotation. As shown in Fig. 6, the stud 20 is a composite structure comprising a central bolt and a sleeve surrounding the bolt, the sleeve being omitted from the schematic Figs. 1 and 2. By the action of the machine the side portions 12, 12 of the wire are coiled or wound on the arbor to produce coils 22, 22 as shown in Fig. 2. The arbor 18 and the dog 16 collectively constitute means carried by the spindle for engaging a wire to effect winding thereof to form a spring.

Machine as shown in Figures 3 to 12.

The machine comprises a main frame for carrying or supporting all of the operative parts other than some portions of the electrical equipment which may be separately supported as hereinafter explained. The frame of

the machine comprises vertical front and rear plates 24 and 26 which are connected near the corners thereof by means of transverse angle bars 28, 28. The angle bars may be secured to the plates by means of bolts 30, 30. A cover 32 is provided which extends between the front and rear plates at the top and end edges thereof, the cover enclosing the space between the plates. The front and rear plates and the parts carried thereby are supported upon a horizontal base 34.

Supported in suitable bearings carried by the front and rear frame plates is a transverse main drive shaft 36. Secured to the shaft 36 between the front and rear plates and near the rear plate is a sprocket wheel 38. An endless drive chain 40 passes around the sprocket wheel 38 and also around a sprocket wheel at 42, the chain extending through an opening in the right portion of the cover 32. The sprocket wheel 42 is driven by a motor 44 which is shown only in the wiring diagram in Fig. 13. An adjustable change speed mechanism may be interposed between the motor 44 and the sprocket wheel 42.

As shown in Fig. 5, a bearing supporting stud 46 is mounted in a block 48 carried by the rear frame plate 26, this stud projecting forwardly. A large bull gear 50 is rotatably mounted on the stud 46 by means of a bearing 52. The bull gear 50 meshes with a pinion 54 on the drive shaft 36, as shown in Fig. 4, the said gear 50 being continuously rotated in the counterclockwise direction when the drive shaft is rotated.

Supported in suitable bearings carried by the front and rear plates 24 and 26 and near the bottoms thereof is a transverse rockshaft 56. Secured to the rockshaft is an arm 58 which carries a gear segment 60, the gear segment being concentric with the axis of the rockshaft.

Secured to the front face of the bull gear 50 are two parallel guides spaced equally from a radial plane through the center of the gear. One of the said guides is shown at 62 in Fig. 5. A block 64 fits between the guides and is adjustable radially along the face of the gear 50. A manually rotatable screw 66 carried by the gear serves to radially adjust the block 64 and to hold it in adjusted position. The arm 58 has a radial slot 68 therein, and a roller 70 carried by the block 64 fits the said slot 68. It will be understood that when the gear 50 is rotated, the roller 70 moves in the slot 68 to oscillate the arm 58 and the gear segment 60. The extent of oscillation can be changed by changing the distance of the roller 70 from the axis of rotation. For the particular setting illustrated, the gear segment is movable as shown in Fig. 4 from an extreme left position as indicated at 60^a to an extreme right position as indicated at 60^b.

An intermediate shaft 72 is supported in suitable bearings carried by the respective front and rear plates 24 and 26. Secured to the shaft 72 is a gear 74 which meshes with the gear segment 60. As the gear segment is oscillated the gear 74 and the shaft 72 are rotated successively in opposite directions.

At least one transverse horizontal spindle is provided which is rotated by the intermediate shaft 72. Preferably, there are two such spindles 76 and 78 widely spaced horizontally and located near the respective ends of the machine. As clearly shown in Fig. 6, the left spindle 76 is supported at the front by a bearing mounted in a bearing block 80 carried by the front frame plate 24. At the rear of the spindle 76 and in alignment therewith is a short spindle drive shaft 82 supported on the rear frame plate 26 by a bearing 84. The drive shaft 82 has a flange 86 at its front end and said drive shaft is centrally recessed to receive the rear end portion of the spindle. The spindle is supported at the rear by a bearing 88 within said recess in the drive shaft 82, it being clear that the drive shaft is rotatable independently of the spindle.

The spindle 76 projects at the front beyond the front plate 24 and beyond the bearing block 80 and it has a tapered opening for receiving a driving member for the arbor 18 which member may be a chuck having a flange

89. Preferably there are two oppositely disposed blocks or keys 90 and 92 which are carried by the spindle, these being more clearly shown in Fig. 11. The said blocks or keys enter and fit slots in the chuck flange 89, a positive driving being thus provided for the chuck.

5 A suitable tool is provided at the front of the machine for engaging the legs 12, 12 of the wire 10 while the wire is being coiled or wound on the arbor 18. The form of the tool may be widely varied, but as shown the tool is merely 10 the beforementioned stud 26. The stud is carried by a bracket 93 and is adjacent the upper end thereof. The bracket 93 is held in place by bolts 94 and 95 which engage the front frame member 24. The bracket preferably has an arcuate slot for receiving the lower bolt 95, the bracket being thus adjustable about the axis of the upper bolt 94.

15 The right spindle 78 is similar to the left spindle 76 and is similarly mounted, except that it is reversed in position. It is provided at the rear with a chuck which is similar to 20 that for the spindle 76 and which is similarly connected. A stud 26 is provided which is similar to that at the front and which is similarly mounted. There is a drive shaft 96 25 for said spindle 78 at the front thereof, this drive shaft being similar to the drive shaft 82 for the spindle 76.

25 Located between the intermediate shaft 72 and the spindle 76 is a transverse horizontal shaft 98 supported by suitable bearings carried by the front and rear frame plates. Gears 100 and 102 are secured respectively to the intermediate shaft 72 and to the shaft 98. An idler gear 30 104 is provided which meshes with the said gears 100 and 102, the idler gear being rotatable on a stud 106 carried by the rear frame plate 26. The shaft 98 projects beyond the rear plate 26 and the spindle drive shaft 82 similarly projects beyond said rear plate. Meshing gears 35 108 and 110 are secured respectively to the projecting portions of the shafts 98 and 82. The gears 108 and 110 are readily removable and other gears may be substituted to provide a different speed ratio between said shafts. A removable cover, not shown, may be provided for the gears 108 and 110. 40 By means of the described gearing the spindle drive shaft 82 is rotated successively in opposite directions, the successive directions of rotation being opposite those of the intermediate shaft 72.

45 Located between the intermediate shaft 72 and the spindle 78 is a transverse horizontal shaft 112 similar to the shaft 98 and similarly supported by suitable bearings carried by the front and rear frame plates. A gear 114 is secured to the shaft 112, this gear meshing with the aforesaid gear 100 on the intermediate shaft 72. The shaft 50 112 projects beyond the front plate 24 and the spindle drive shaft 96 similarly projects beyond said front plate. Meshing gears 116 and 118 similar to the gears 108 and 110 are secured respectively to the projecting portions of the shafts 112 and 96. The gears 116 and 118 are readily 55 removable and other gears may be substituted to provide a different speed ratio between the shafts 112 and 96. The speed ratio between the shafts 112 and 96 is ordinarily exactly the same as the speed ratio between the shafts 98 and 82. A removable cover, not shown, may also be provided for the gears 116 and 118. By means of the described gearing the spindle drive shaft 96 is rotated successively in opposite directions, the successive directions of rotation being the same as those of the intermediate shaft 72 and opposite those of the spindle drive shaft 82.

60 65 As shown in Fig. 6, a clutch 120 is provided by means of which the spindle drive shaft 82 may be connected with or disconnected from the spindle 76. The clutch is preferably of the electromagnetic type and it is adapted to be engaged and disengaged by means including electric circuits and switches as hereinafter explained in detail. Any suitable electromagnetic clutch may be used and the clutch and its associated parts as shown are intended to be merely illustrative. The clutch 120 includes a rotatable cylindrical member 122 which is rigidly connected with the spindle by means of a spindle driving 70 75

disc 124. The cylindrical member 122 carries an annular magnet coil 125. The coil is connected in an electric circuit by means of slip rings 128, 128 and by means of stationary brushes 130, 130, the brushes being carried by a bracket 132 on the cover plate 32. The clutch 120 includes a rotatable armature 134 which is connected with the spindle drive shaft 82 for rotation in unison therewith.

When the clutch magnet coil 126 is energized, the clutch armature 134 is moved longitudinally of the shaft 82 and into frictional engagement with a friction member adjacent the magnet and movable therewith and the spindle 76 is rotated in unison with the said armature and with the spindle drive shaft. When the magnet coil 126 is de-energized, the armature 134 is released from frictional engagement with the said magnet, and the spindle drive shaft 82 and the armature 134 are freely rotatable independently of the spindle. As will be explained, the clutch magnet may be only partly energized.

A brake 136 is provided for quickly stopping the rotation of the spindle 76. When the brake is engaged it serves to prevent rotation of the spindle. When the brake is disengaged the spindle is free for rotation by the clutch 120. The brake 136 is preferably of the electromagnetic type. Any suitable electromagnetic brake may be used but as shown the brake 136 is similar to the clutch 120. The brake includes a cylindrical member 138 which is nonrotatable and which is preferably rigidly connected with the block 80 which supports the front spindle bearing. The cylindrical member 138 carries an annular magnet coil 140. The brake also includes a rotatable armature 142 which is connected to the spindle for rotation therewith by means of a disc 144 secured to the spindle.

When the brake magnet coil 140 is energized, the brake armature 142 is moved longitudinally of the spindle and into frictional engagement with a nonrotatable friction member adjacent the magnet. The frictional engagement stops rotation of the spindle 76 and holds the spindle in a fixed rotative position. When the brake magnet is de-energized, the brake armature is released from frictional connection with the magnet and the spindle is free so that it can be rotated by the clutch 120. As will be explained, the brake magnet 140 may be only partly energized.

A clutch 146 is provided for driving the spindle 78, this clutch being similar to the clutch 120 and having a magnet coil similar to the magnet coil 126. A brake 150 is provided for the spindle 78, this brake being similar to the brake 136 and having a magnet coil similar to the magnet coil 140. The clutch 146 and the brake 150 operate in the same manner as described in connection with the clutch 120 and the brake 136.

As shown in Figs. 4, 7, 8 and 9 a cam operated switch mechanism is provided. The mechanism includes a cam shaft 154 which is mounted in suitable bearings on the front and rear frame plates 24 and 26. As shown in Figs. 4 and 5, a gear 156 is provided which is connected with the bull gear 50. The gear 156 meshes with a gear 158 on the cam shaft 154, said shaft being thus continuously rotated. The gears 156 and 158 are of the same diameter and it will be apparent that the cam shaft 154 makes one revolution during each cycle of operation.

Secured to the cam shaft 154 are four cams 160, 162, 164 and 166. Carried by the base 34 is a bracket 168 which carries four switches 170, 172, 174 and 176 corresponding respectively to said four cams. A bracket 177 is carried by the front frame plate 24, and four push rods 178, 179, 180 and 181 are mounted in the bracket for vertical movement, the tops of the said push rods being engageable respectively by the cams 160, 162, 164 and 166.

The push rod 178 engages a pivoted lever 182 which is biased upwardly by a spring 183, the lever being oscillated when the rod is reciprocated. The lever 182

engages and operates a control lever 184 on the switch 170 which is of the ratchet type. As shown in the diagram of electrical connections, the switch 170 comprises two pairs of contacts 170^a and 170^b. For convenience of description the contacts of the two pairs will sometimes be referred to as separate switches. Upon alternate operations the switch 170^a is closed and the switch 170^b is opened and upon intervening operations the switch 170^a is opened and the switch 170^b is closed.

Each of the switches 172, 174 and 176 has a control lever 186 which is moved downwardly by the corresponding push rod. The levers 186 are spring biased to move the push rods upwardly. As shown in the diagram of electrical connections, the switch 172 comprises two pairs of contacts 172^a and 172^b and the switch 174 comprises two pairs of contacts 174^a and 174^b. For convenience of description the contacts of the said pairs will sometimes be referred to as separate switches. Upon each operation the switch 172^a is closed and the switch 172^b is simultaneously opened and thereafter the switch 172^a is opened and the switch 172^b is simultaneously closed. Similarly, upon each operation the switch 174^a is closed and the switch 174^b is simultaneously opened and thereafter the switch 174^a is opened and the switch 174^b is simultaneously closed. The switch 176 has only one pair of contacts.

The cams 160, 162, 164 and 166 are angularly adjustable on the shaft 154 so as to operate the switches in the proper timed relationship. The exact shapes and positions of the cams are not shown, but the necessary timing will be apparent from the description which will be given in connection with the electrical diagram in Fig. 13.

As shown in Figs. 3, 6 and 10, a cam operated switch mechanism is provided for each spindle. As shown the spindle 76 carries a cam 188, which operates a pivoted lever 189 on a bracket 190 secured to the adjacent angle-bar 28. The bracket 190 carries a switch 192, which is operated when the lever 189 is moved by the cam 188. As shown in the diagram of electrical connections, the switch comprises two pairs of contacts 192^a and 192^b. For convenience of description, the contacts of said pairs will sometimes be referred to as separate switches. Upon each operation the switch 192^a is opened and the switch 192^b is simultaneously closed and thereafter the switch 192^a is closed and the switch 192^b is simultaneously opened.

The spindle 78 carries a cam 193 which is similar to the cam 188, this cam operating a switch 194 which is similar to the switch 192. As shown in the diagram of electrical connections, the switch 194 comprises two pairs of contacts 194^a and 194^b. For convenience of description, the contacts of said pairs will sometimes be referred to as separate switches. Upon each operation the switch 194^a is opened and the switch 194^b is simultaneously closed and thereafter the switch 194^a is closed and the switch 194^b is simultaneously opened.

As shown in Figs. 3, 4, 11 and 12, a mechanism is provided for each spindle for definitely positioning or stopping it in its starting position at the beginning of each cycle, that is, at the beginning of each rotation in the winding direction. The said mechanism is shown in detail for the spindle 76 and it will be understood that an identical mechanism is provided for the spindle 78.

As previously stated, the blocks or keys 90 and 92 on the spindle enter slots in the chuck flange 89. As more clearly shown in Fig. 11, the periphery of the flange 89 is curved inwardly adjacent the left faces or shoulders 198 and 200 of the blocks so as to provide notches. A bracket 202 is secured to the front frame plate 24, and a lever 204 is horizontally pivoted at 206 to said bracket. The lever 204 has a notch providing an abutment at 208 which is engageable with the shoulder 198 of the block 90 when the lever is in its lower position as shown in Fig. 11. The lever is biased to its said lower position by a spring 210.

and the periphery of the flange 89 limits downward movement.

Mounted on the bracket 202 is a solenoid 212 having a vertically movable core or plunger 213. A link 214 is pivotally connected at its upper end with the plunger 213 and is pivotally connected at its lower end with the lever 204. When the solenoid is energized, the plunger 213 is moved upwardly so as to swing the lever 204 upwardly in opposition to the spring 210. The solenoid normally holds the lever 204 in its upper position so that the abutment 208 is out of the paths of movement of the blocks 90 and 92. When the solenoid is de-energized, the lever is moved downwardly by the spring 210 to the extent permitted by the periphery of the flange 89, the abutment 208 being then in position to engage the shoulder 198 of the block 90. As shown in Fig. 11 said abutment 208 is slightly spaced from said shoulder 198. The purpose and manner of operation of the last-described mechanism will be hereinafter more fully explained.

The spindle has been shown and described as initially rotatable in the clockwise direction to effect winding. However, the spindle may be initially rotatable in the counterclockwise direction to effect winding. When the spindle is to be initially rotated in the counterclockwise direction, the lever 204 is reversed in position as shown in Fig. 12. The lever is provided with an additional abutment 215. When the lever 204 is reversed and is in its lower position the abutment 215 is in position to engage the shoulder 209 on the block 92.

The spindle 78 is provided with a positioning mechanism similar to that described for the spindle 76. This mechanism includes a solenoid 216 similar to the solenoid 212.

Electrical control as shown in Fig. 13

Fig. 13 shows the various electrical connections for the machine shown in Figs. 3 to 12. It will be understood that some of the electrical units may be mounted on a separate panel rather than on the main frame of the machine.

Main alternating current leads 218, 220 and 222 are provided which are controlled by a main switch 224. The said main leads are connected with forward leads 226, 228 and 230 for the motor 44 and said main leads are also connected with reverse leads 232, 234 and 236 for said motor.

The primary coil of a transformer 238 is connected between the main leads 218 and 222. Connected with the secondary coil of the transformer are two leads 240 and 242 having a suitable relatively small potential between them which may be 110 volts. Connected with another portion of the secondary coil of the transformer is a lead 244. The potential between the leads 240 and 244 is greater than that between the leads 240 and 242 and may be 220 volts.

Included in a connection 246 between the leads 240 and 242 is the coil of a forward motor starter relay 248 and an initially open manually operable forward starter switch 250^a. Connected in parallel with the switch 250^a is a shunt 252. Included in another connection 254 between the leads 240 and 242 is the coil of a reverse motor starter relay 256 and an initially open manually operable reverse starter switch 258^a. Connected in parallel with the switch 258^a is a shunt 260. Included in the connection 254 is an initially closed switch 250^b, this being mechanically connected to be opened when the forward starter switch 250^a is closed. Included in the connection 246 is an initially closed switch 258^b, this being mechanically connected to be opened when the reverse starter switch 258^a is closed.

The forward motor leads are controlled by a switch 248^a and the reverse motor leads are controlled by a switch 256^a. Included respectively in the shunts 252 and 260 are initially open switches 248^b and 258^b. Included

respectively in the connections 246 and 254 are initially closed switches 256^c and 248^c. The switches 248^a, 248^b and 248^c are mechanically connected with the forward relay 248 so that upon energization of the relay the switches 248^a and 248^b are closed and the switch 248^c is opened. The switches 256^a, 256^b and 256^c are mechanically connected with the reverse relay 256 so that upon energization of the relay the switches 256^a and 256^b are closed and the switch 256^c is opened.

10 Upon manual closing of the forward starter switch 250^a the forward relay 248 is energized and the switch 250^b is opened. The opening of the switch 250^b prevents any possible energization of the reverse relay 256. The energization of the relay 248 closes the switch 248^a to

15 start the motor in the forward direction and closes the switch 248^b to maintain the circuit through the coil after the starter switch 250^a is opened. At the same time the switch 248^c is opened to prevent any possible energization of the reverse relay after the switch 250^b is closed.

20 Upon manual closing of the reverse starter switch 258^a the reverse relay 256 is energized and the switch 258^b is opened. The opening of the switch 258^b prevents any possible energization of the forward relay 248. The energization of the relay 256 closes the switch 256^a to start

25 the motor in the reverse direction and closes the switch 256^b to maintain the circuit through the relay after the starter switch 258^a is opened. At the same time the switch 256^c is opened to prevent any possible energization of the forward relay after the switch 258^b is closed.

30 An initially closed motor stop switch 262 is connected in series with the connections 246 and 254. The manual opening of the switch 262 serves to de-energize the relay that has been previously energized, thus restoring all of the other switches to their initial positions and stopping the motor.

Included in a connection 264 between the leads 240 and 242 is the coil of a relay 266 for controlling the operation of the left spindle 76. Also included in the connection 264 is an initially open starter switch 268 and an initially closed stop switch 270. Connected in parallel with the switch 268 is a shunt 272. The switch 268 when closed energizes the relay 266 to start the operation of the left spindle and the switch 270 when opened de-energizes the relay 266 to stop the operation of the left spindle, all as hereinafter more fully explained.

45 The switches 268 and 270 are enclosed within a switch box 274 mounted on the machine at the left end thereof as shown in Figs. 3 and 4. Mechanically connected with the relay 266 for operation thereby are switches 266^a, 266^b and 266^c. The switches 266^a and 266^b are closed when the relay is energized and are open when the relay is de-energized. The switch 266^c is open when the relay is energized and is closed when the relay is de-energized. The switch 266^a is included in the shunt 272 to maintain the circuit through the relay after the switch 268 has been opened. The several switches are shown in the positions which they occupy with the relay energized.

50 Included in a connection 276 between the leads 240 and 242 is the coil of a relay 278 for controlling the operation of the right spindle 78. Also included in the connection 276 is an initially open starter switch 280 and an initially closed stop switch 282. Connected in parallel with the switch 280 is a shunt 283. The switch 280 when closed energizes the relay 278 to start the operation of the right spindle and the switch 282 when opened de-energizes the relay 278 to stop the operation of the right spindle, all as hereinafter more fully explained. The switches 280 and 282 are enclosed within a switch box 284 mounted on the machine at the right end thereof

60 as shown in Figs. 3 and 4. Mechanically connected with the relay 278 for operation thereby are switches 278^a, 278^b and 278^c. The switches 278^a and 278^b are closed when the relay is energized and are open when the relay is de-energized. The switch 278^c is open when the relay is energized and

70

is closed when the relay is de-energized. The switch 278^a is included in the shunt 283 to maintain the circuit through the relay after the switch 280 has been opened. The several switches are shown in the positions which they occupy with the relay energized.

By means of a connection 286 and return connections 288 and 290, the solenoids 212 and 216 are connected with the main leads 218, 220 and 222. The cam operated switch 176 is included in the connection 288 for energizing and de-energizing both solenoids. When the switch 176 is open, as shown in Fig. 13, the solenoids are de-energized and the levers 204 controlled by said solenoids are in their lower positions as shown in Figs. 4 and 11. Preferably a manually operable switch 292 is provided in parallel with the switch 176. When the switch 292 is closed the solenoids are continuously energized. However, the switch 292 is ordinarily open and does not interfere with the control of the solenoids by the switch 176.

Connected between the leads 240 and 244 is a rectifier 294 from which extend leads 296 and 298. The said leads 296 and 298 are supplied with direct current at a potential which may be 220 volts.

The electrical connections and apparatus which are controlled by the relay 266 and which serve primarily to control the left spindle 76 will first be described.

The magnet coil of the clutch 120 for the left spindle 76 is included in a main connection 300 between the leads 296 and 298. Also included in the connection 300 is the switch 266^b, the cam operated switch 172^a, a hot wire resistance 302 which may be a lamp bulb, and the cam operated ratchet switch 170^a. A condenser 304 is connected in parallel with the clutch magnet coil. A manually operable switch 305^a is connected in parallel with the switch contacts 170^a and for present purposes it will be assumed that the switch 305^a is closed.

A shunt connection 306 for the magnet coil of the clutch 120 is provided in parallel with the main clutch connection 300, this shunt connection including the cam operated switch 172^b, the cam operated switch 192^a, a fixed resistance 308 and a variable resistance 310. The switch 172^b is hereinafter sometimes designated as a control switch, and the switch 192^a is hereinafter sometimes designated as a first stop switch.

A connection 312 extends between a point in the clutch shunt connection 306 intermediate the switches 172^b and 192^a and the lead 298. This connection includes the cam operated switch 192^b and the magnet coil of the brake 136 for the left spindle. A condenser 314 is connected in parallel with the brake magnet coil 140. The switch 192^b is hereinafter sometimes designated as a second stop switch. It will be observed that the first and second stop switches 192^a and 192^b are in parallel with each other and in series with the control switch 172^b.

A connection 316 is provided which is in parallel with the connection 312 except for the switch 192^b. The connection 316 includes a resistance 318 and the coil of a time delay relay 320. An initially closed switch 320^a is provided in the connection 312, this switch being operable by the relay 320. The relay 320 upon energization serves to open the switch 320^a after a predetermined small interval of time which may be about .4 of a second.

A connection 322 is provided in parallel with the switch 320^a, this connection including a fixed resistance 324 and a variable resistance 326.

A connection 328 is provided between the lead 296 and the connection 322, this connection including the switch 266^c and an initially closed manually operable release switch 330. The switch 330 is in said switch box 274.

The electrical connections and apparatus which are controlled by the relay 278 and serve primarily to control the right spindle 78 are similar to those for the left spindle 76 and they will now be described.

The magnet coil of the clutch 146 for the right spindle

75

78 is included in a connection 332 between the leads 296 and 298. Also included in the connection 332 is the switch 278^b, the cam operated switch 174^a, a hot wire resistance 334 which may be a lamp bulb, and the cam operated ratchet switch 170^b. A condenser 336 is connected in parallel with the clutch magnet coil. A manually operable switch 305^b is connected in parallel with the switch 170^b. The switch 305^b will be assumed to be closed, this switch being mechanically connected with the switch 305^a so that both switches are opened and closed in unison.

A connection 338 is provided in parallel with the switch 174^a and the resistance 334, this connection including the cam operated switch 174^b, the cam operated switch 194^a, a fixed resistance 340 and a variable resistance 342.

A connection 344 extends between a point in the connection 338 intermediate the switches 174^b and 194^a and the lead 298. This connection includes the cam operated switch 194^b and the magnet coil of the brake 150 for the right spindle. A condenser 346 is connected in parallel with the brake magnet coil.

A connection 348 is provided which is in parallel with the connection 344 except for the switch 194^b. The connection 348 includes a resistance 350 and the coil of a time delay relay 352. An initially closed switch 352^a is provided in the connection 344, this switch being operable by the relay 352. The relay 352 upon energization serves to open the switch 352^a after a predetermined small interval of time which may be about .4 of a second.

A connection 354 is provided in parallel with the switch 352^a, this connection including a fixed resistance 356 and a variable resistance 358.

A connection 360 is provided between the lead 296 and the connection 354, this connection including the switch 278^c and an initially closed manually operable release switch 362. The switch 362 is in said switch box 284.

Operation of machine

The machine requires two operators when springs are to be wound at both spindles. One operator stands at the left end of the machine so that he can conveniently remove the successive completed springs from the arbor carried by the left spindle 76 and so that he can put in place successive new wires 10. The other operator stands at the right end of the machine so that he can conveniently remove the successively completed springs from the arbor carried by the right spindle 78 and so that he can put in place successive new wires 10. The operator at the left can control his own spindle by means of the switches 268, 270 and 330 in the switch box 274. The operator at the right can control his own spindle by means of the switches 280, 282 and 362 in the switch box 284.

The bull gear 50 and the segment 60 together with various parts operated thereby constitute power operated means having successive cycles of operation. The clutch and brake for each spindle together with the electrical circuits and switches therefor constitute a control means for the spindle operable by said power operated means.

The machine can be operated so that a spring is wound by each spindle during each cycle of the power operated means. Alternatively the machine can be operated so that a spring is wound by each spindle during each alternate cycle, the timing preferably being such that one spindle is idle while the other is operating. The first mentioned manner of operation will be first described. For this manner of operation the switches 305^a and 305^b are closed.

In describing the operation of the machine it will be assumed that the left spindle is rotated in the clockwise direction to effect winding, the dog 16 being positioned as shown in Fig. 4 with its hook facing in the clockwise direction. Similarly, it will be assumed that the right spindle 78 is rotated in the counterclockwise direction, as viewed in Fig. 4. However, as viewed by the operator, 75 the spindle 78 is rotated in the clockwise direction, the

manner of operation being exactly the same as that of the spindle 76. It will also be assumed that the switches 268 and 280 have been closed so that both spindles are ready for operation.

It will also be assumed that one cycle has been completed and that two wires have been coiled or wound at the respective spindles to the shape shown in Fig. 2. Each operator has removed the dog from the arbor, the wound spring being removed with the dog. The spring has been separated from the dog and a new wire 10 has been engaged with the dog and the dog has been re-engaged with the arbor, as shown in Figs. 1, 3 and 4. At the option of the operator the wire 10 may be engaged with the dog either before or after the dog is re-engaged with the arbor. In order to facilitate placement of the wire and the dog, the spindle is initially positioned so that the dog is located substantially as shown in Fig. 4, the legs 12 of the wire 10 being spaced downwardly from the stud 20. It will be seen that before winding starts the spindle and the dog must be rotated sufficiently to engage the legs 12 with the stud. This amount of initial rotation will be assumed to be $\frac{1}{16}$ of a turn.

In setting up the machine the roller 70 has been so adjusted and the gears 108, 110 and 116, 118 have been so selected that each spindle makes the required number of revolutions or turns during the movement of the gear segment 60 in one direction, that is, from left to right. By way of example, it will be assumed that the completed spring is to have $5\frac{1}{4}$ turns. The spring will recoil or unwind to a limited extent to effect stabilization and the unwinding will be assumed to be $\frac{1}{2}$ of a turn. Furthermore, $\frac{1}{16}$ of a turn is required, as previously explained, to bring the legs 12 of the wire into engagement with the stud 20. Therefore, the extent of spindle rotation must be $5\frac{1}{16}$ turns.

The following description relates more particularly to the left spindle 76 and to the parts directly associated therewith, it being understood that the manner of operation for the spindle 78 is the same. At the beginning of winding, the several parts are in the positions shown in Figs. 4 and 14, and the several switches are in the positions shown in Fig. 13. The switches 172^a and 172^b have been respectively closed and opened by the cam 162. By means of the closed switch 172^a a circuit has been established through the magnet coil of the clutch 120. This circuit extends through the switch 305^a which has been assumed to be closed. The clutch connects the spindle 76 with the drive shaft 32 and the spindle is therefore rotated. The open control switch 172^b insures the opening or breaking of the circuit through the magnet coil of the brake 136, the brake being disengaged to permit spindle rotation. At the start of spindle rotation in the winding or clockwise direction the abutment 208 on the lever 204 is in engagement with the shoulder 198 of the block 90, the starting position of the spindle being thus accurately determined as shown in Fig. 4 and the spindle being free to rotate in the clockwise or winding direction. Immediately after the start of spindle rotation, the cam 166 acts to close the switch 176 and thus energize the solenoid 212 and upwardly move the plunger thereof so that the lever 204 is swung to its upper position with its abutment 208 out of the paths of the blocks 90 and 92 on the spindle. During winding the gear segment 60 moves from its extreme left position shown at 60^a in Figs. 4 and 14 to the extreme right position shown at 60^b in Figs. 4 and 15. The clutch is maintained engaged and the brake is maintained disengaged so as to continue the rotation of the spindle during the entire movement of the segment. The said movement of the gear segment rotates the spindle to the required extent, which for the example given is $5\frac{1}{4}$ turns. In other words, the spindle and the dog have been rotated 5 complete turns and have been additionally rotated $\frac{1}{16}$ of a turn beyond the starting position, as represented by the angle a .

When the parts reach the positions shown in Fig. 15, the gear segment 60 starts its return movement toward the left. The clutch is still engaged and the brake is still disengaged, and the direction of rotation of the drive shaft and spindle is reversed. During the initial portion of the reverse rotation the spring unwinds to a limited extent, but the unwinding is at a relatively slow rate as determined by the relatively slow reverse rotation of the spindle. This prevents any unduly rapid unwinding. The extent of unwinding is ordinarily less than a complete turn and in the example given it is $\frac{1}{2}$ of a turn.

When the parts reach the positions shown in Fig. 16, the unwinding of the spring has preferably been completed, or substantially completed. If the unwinding has been exactly completed, the dog is spaced from the starting position by the angle b , which is $\frac{5}{16}$ of a turn. Thereupon the switch 172^a is opened by the cam 162 and the switch 172^b is simultaneously closed. The closing of the switch 172^b establishes an alternate or shunt circuit 20 through the magnet coil of the clutch 120, this alternate circuit including the first stop switch 192^b which is still closed and also includes the resistances 308 and 310. By means of the last described circuit a reduced voltage is applied to the clutch magnet coil 126. The clutch 25 continues to rotate the spindle in the reverse direction but with smaller current, the clutch being thus prepared for rapid disengagement of the spindle when the circuit is later broken.

The clutch operating with reduced current continues 30 to rotate the spindle in the reverse direction to an extent which is sufficient to restore the spindle and dog approximately, but preferably not quite, to their initial starting positions, as shown in Fig. 17. The small spacing from the starting position is represented by the angle c . This 35 additional reverse rotation is shown as being a little more than $\frac{1}{4}$ of a turn, and it is in any event less than a complete turn. The said additional reverse rotation serves to separate the legs 12, 12 of the wound spring from the stud 20 so that the spring can be readily removed. 40 When the parts reach the positions shown in Fig. 17, the first stop switch 192^a is opened by the cam 188 on the spindle 76 and the second stop switch 192^b is simultaneously closed. It will be observed that the stop switches 192^a and 192^b are operated during each turn of the 45 spindle in the winding direction, and during a partial turn in the unwinding direction but that no circuits are broken or made thereby while the control switch 172^b remains open. The first opening of the first stop switch 192^a after the control switch 172^b has been closed breaks the 50 alternate or shunt circuit through the magnet coil of the clutch 120 to disengage the clutch and the simultaneous closing of the second stop switch 192^b establishes a circuit through the magnet coil of the brake 136 and also establishes a circuit through the coil of the relay 320. 55 Full voltage is initially applied to the brake magnet coil and the brake acts to substantially instantaneously stop the rotation of the spindle. The relay 320 after a predetermined time lag, which may be .4 of a second, acts to open the switch 320^a. This cuts out the direct connection to the brake magnet coil, said coil being then energized through the resistances 324 and 326. By reason of said resistances a reduced voltage is applied to the brake magnet coil, but the voltage is sufficient to enable the brake to hold the spindle against rotation. Inasmuch as the cam 188 which operates the stop switches 192^a and 192^b is directly on the spindle, said switches are so operated as to stop the spindle in a reasonably accurately predetermined position.

It will be observed that there is provided a control 60 means which includes an element, specifically the cam 162, which is movable to a controlling position after a predetermined substantial extent of the spindle rotation, said control means also including the corresponding switches 172^a and 172^b. A second control means is provided which includes the stop switches 192^a and 192^b and

the operating cam 188 therefor. This second control means is dependent for its operation upon the prior movement of the movable element or cam 162 of the first control means to its switch operation position and upon the prior operation of the said control switches 172^a and 172^b. After the spindle has rotated through an additional predetermined fraction of a turn, the second control means serves to substantially simultaneously disengage the clutch and engage the brake to stop the spindle.

It will also be observed that the circuit for the clutch includes two parallel connections 300 and 306. The switch 172^a is an initially closed switch in the main clutch connection 300. The switch 172^b is an initially open control switch in the shunt connection 306 for the clutch and in the circuit connection 312 for the brake. The cam 162 constitutes means operable in timed relation with the spindle for opening the main clutch switch 172^a and for closing said control switch 172^b after the spindle has rotated to a predetermined substantial extent. The switch 192^a is a normally closed first stop switch in the clutch shunt connection 306, and the switch 192^b is a normally open second stop switch in the brake connection 312. The spindle cam 188 constitutes means for simultaneously operating the stop switches to open one of them and to close the other during each spindle rotation, the first stop switch 192^a being first opened after the opening of the main clutch switch 172^a and the closing of the control switch 172^b serving to open the circuit through the clutch and the second stop switch 192^b when first closed after the closing of the control switch 172^b serving to close the circuit through the brake.

The last preceding description relates more particularly to the spindle 76 and the parts associated therewith. It will be understood however that the switches 174^a, 174^b and 194^a, 194^b operate simultaneously with the switches 172^a, 172^b and 192^a, 192^b to control the spindle 78 in the same manner as described for the spindle 76.

At or about the same time that the switches 192^a, 192^b and 194^a, 194^b are operated to stop the spindles, the switch 176 is opened by the cam 166 to de-energize the solenoids 212 and 216. When the solenoids are de-energized the lever 204 for each spindle is moved downwardly to the position shown in Fig. 11, the abutment 208 on the lever being adjacent the shoulder 198 of the block 90. Each spindle is stopped in such a position that there is a slight space between the abutment 208 and the shoulder 198 as shown in Fig. 11.

After the parts have reached the positions shown in Fig. 17, the gear segment 60 continues to move toward the left, the spindles being held by the brakes and being stationary. During this period of spindle dwell the operators remove the completed springs and replace them with wires 10 as previously described.

Near the end of the reverse rotation of the drive shaft or near the beginning of the rotation thereof in the winding direction, the switches 172^b and 174^b are simultaneously opened by their respective cams and at the same time the switches 172^a and 174^a are simultaneously closed. Preferably the switches are operated with the parts in the position shown in Fig. 18. In this position the gear segment 60 has moved nearly, but not quite, to its extreme left position as shown in Figs. 4 and 14 and the drive shaft has nearly, but not quite, completed its reverse rotation. The positions of the spindle and dog are the same as shown in Fig. 17. The Fig. 18 position is reached after the aforesaid period of spindle dwell and the completed springs have been replaced by new wires 10. As the result of the described operation of the switches the circuits through the magnet coils of the brakes 136 and 150 are broken and the circuits through the magnet coils of the clutches 120 and 146 are closed. By reason of the hot wire resistances 302 and 334 the clutch magnet coils have an initial high voltage to quickly start the rotation of the spindles. After the resistances 302 and 75

334 have become heated a reduced voltage is applied to the coils.

Inasmuch as the parts are in the positions shown in Fig. 18 when the clutches are first engaged, the spindles are initially moved slightly in the reverse directions. Referring particularly to the spindle 76, it will be seen from Fig. 11 that the spindle is initially moved in the counterclockwise direction to engage the shoulder 198 of the block 90 with the abutment 208 of the lever 204. The engagement of said parts takes place when the segment has moved to its extreme left position, the several parts being in the positions shown in Figs. 4 and 14. Ordinarily there is a small slippage at the clutch as said parts engage. The said engagement accurately locates the spindle in its required starting position. The final locating of the spindles in their proper starting positions is important, as stopping of the spindles by the brakes is unavoidably subject to minor inaccuracies. If the final locating means were not provided, any errors in the spindle positions as determined by the brakes would accumulate through successive cycles and the starting positions would soon be substantially different from the proper starting positions, thus resulting in the winding of the springs to extents substantially greater or less than required.

Immediately after the segment starts to move toward the right to start the movement of the spindles in the winding directions, the switch 176 is closed by the cam 166 to energize the solenoids 212 and 216 and to thus move the levers 204 to their upper inoperative positions. It will be observed that the solenoid 212 and the control therefor constitute automatic means for holding the abutment 208 out of its operative position in the path of movement of the shoulder 198 during rotation of the spindle in the winding direction and during the initial reverse rotation thereof. The said automatic means serves to cause the shoulder to move to its operative position during the final reverse movement of the spindle to its starting position.

It will be observed that the bull gear 50 and the roller 70 are rotated in the counterclockwise direction, as viewed in Fig. 4 and in Figs. 14 and 18. They move through less than $\frac{1}{2}$ of a turn while the segment 60 moves toward the right to effect winding. They move through more than $\frac{1}{2}$ of a turn while the segment moves toward the left. This gives the maximum dwell between the Fig. 17 position and the Fig. 18 position to enable the operators to remove the completed springs and put new wires in place.

It will be seen that each operator always has complete control of his own spindle. Referring particularly to the left spindle 76, it will be observed that the operation of the spindle can be started by the switch 268 and stopped by the switch 270. The stopping of one spindle does not in any way interfere with the continued operation of the other spindle. In fact, when only limited production is required or when only one operator is available, one spindle can remain entirely idle.

In the event of an emergency during winding, the operator can immediately stop his own spindle by opening the corresponding stop switch, such as 270. The opening of the switch 270 de-energizes the relay 266, thus opening the switch 266^b and closing the switch 266^c. The opening of the switch 266^b breaks the circuit through the magnet coil of the clutch 12 and the closing of the switch 266^c establishes a circuit through the magnet coil of the brake 136, thus practically instantaneously stopping rotation of the spindle.

Ordinarily, winding is interrupted only when some emergency is encountered, as for instance when the operator observes that the spring is not being properly wound. With the spindle stopped and with an incomplete spring on the arbor, it is necessary to release the brake in order that the spindle may be rotated to permit removal of the incomplete spring. This is done by opening the switch

330 to temporarily break the circuit through the brake magnet coil. After the incomplete spring has been removed, the switch 330 is closed and the switch 268 is again closed to start the cycle of operations of the spindle.

As thus far described, it has been assumed that the switches 305^a and 305^b are closed. When said switches are closed the control means for each spindle is operative during each cycle of operation of the power operated means. Under some conditions, however, it is impracticable for the operator to remove the completed spring and put a new wire 10 in place during the relatively short interval of time while the gear segment is moving from the Fig. 17 position to the Fig. 18 position. Under such conditions the switches 305^a and 305^b are opened, thus causing the control means for each spindle to be alternately operative and inoperative during successive cycles of operation of the power operated means. As has been stated, the switches 170^a and 170^b are of the ratchet type. Upon one actuation the switch 170^a is open and the switch 170^b is closed. Upon the next actuation the switch 170^a is closed and the switch 170^b is open.

Referring particularly to the spindle 76, it will be seen that with the switch 170^a open during one cycle no circuit is established through the magnet coil of the clutch 120, the spindle therefore remaining idle. It will similarly be seen that with the switch 170^b open during the next following cycle no circuit is established through the magnet coil of the clutch 146, the spindle 78 therefore remaining idle. When the machine is operated as last above-described, the left spindle is stopped with the parts in the Fig. 17 position and it remains stationary until the parts reach the Fig. 18 position of the next following cycle. The right spindle is similarly stopped with the parts in the Fig. 18 position of the cycle following that in which the left spindle is so stopped.

The said switches 305^a and 305^b are optionally operable either to their closed positions or to their open positions. With said switches in closed positions, the control means for each spindle is operative during each successive cycle of operation of the power operated means. With said switches in open positions, the control means for each spindle is alternately operative and inoperative during successive cycles of operation of the power operated means.

In the foregoing description, it has been assumed that each spindle during winding is operated in the clockwise direction as viewed by the operator. To effect winding in the counterclockwise direction, the direction of rotation of the motor 44 is reversed so that the bull gear 50 is rotated in the clockwise direction instead of in the counterclockwise direction. Each lever 204 is reversed in position so as to be located as shown in Fig. 12 with the shoulder 215 engageable with the face 200 of the block 92. Each dog 16, or an alternative similar dog, is positioned with its hook facing in the counterclockwise direction. Each wire 10 is engaged with its dog with the legs 12, 12 positioned below the spindle instead of above it. Each stud 20 is so positioned that the legs 12, 12 of the wire are above the stud instead of below it. Except as above-stated, the manner of operation is similar to that previously described, but all of the relative movements of the parts as illustrated in Figs. 14 to 18 are reversed.

The invention claimed is:

1. A spring winding machine comprising in combination, a spindle rotatable in a winding direction from a predetermined starting position and then reversely, means connected with the spindle for rotation therewith and constructed for engaging a wire to be wound, means including a shoulder rotatable with the spindle and a cooperating abutment for stopping reverse rotation of the spindle when it reaches its said starting position, a gear segment oscillated through a predetermined angle, a drive shaft connected with the segment for rotation thereby first in one direction and then reversely during each segment oscillation, a clutch serving when engaged to connect the

spindle with the drive shaft for rotation therewith, a brake serving when engaged to stop the spindle, automatically operable means for disengaging the brake and simultaneously engaging the clutch near the end of each successive

5 reverse rotative movement of the drive shaft so as to rotate the spindle reversely of its winding direction to its said starting position as determined by said shoulder and abutment which last said means serves to maintain the clutch engaged and the brake disengaged while the drive shaft is rotating in the first said direction to rotate the spindle in the winding direction and to thus effect winding of the wire to form a spring and which last said means further serves to maintain the clutch engaged and the brake disengaged until after the next following reverse rotative movement of the drive shaft has started, means operable in conjunction with said shoulder and abutment for moving one of them relatively to the other to prevent interengagement thereof during rotation of the spindle in the winding direction and during the initial reverse rotation thereof, and means automatically operable during each last said reverse rotative movement of the drive shaft for disengaging the clutch and simultaneously engaging the brake to stop the spindle during continued movement of the segment and continued rotation of the drive shaft and for thus interrupting the reverse rotation of the spindle to provide a period of dwell during which the spindle is stationary, and means for causing the said interrupting means to act so as to provide the said period of dwell after an initial reverse rotation of the spindle and prior to a final 10 reverse rotation thereof so that said final reverse rotation is stopped at said starting position independently of the clutch and as determined by said shoulder and abutment.

2. A spring winding machine comprising in combination, a spindle rotatable in a winding direction from a predetermined starting position and then reversely, means connected with the spindle for rotation therewith and constructed for engaging a wire to be wound, means including a shoulder rotatable with the spindle and a cooperating abutment for stopping reverse rotation of the spindle when it reaches its said starting position, a gear segment oscillated through a predetermined angle, a drive shaft connected with the segment for rotation thereby first in the winding direction and then reversely during each segment oscillation, an electromagnetic clutch serving when engaged to connect the spindle with the drive shaft for rotation therewith, an electromagnetic brake serving when engaged to stop the spindle, means including electrical circuits and switches and automatically operable for disengaging the brake and simultaneously engaging the clutch near the end of each successive reverse rotative movement of the drive shaft to initially rotate the spindle reversely to its said starting position as determined by said shoulder and abutment which last said means serves to maintain the clutch engaged and the brake disengaged while the drive shaft is rotating in the first said direction to rotate the spindle in the winding direction and to thus effect winding of the wire to form a spring and which last said means further serves to maintain the clutch engaged and the brake disengaged until after the next following reverse rotative movement of the drive shaft has started, and means including electrical circuits and switches and automatically operable during each last said reverse rotative movement of the drive shaft for disengaging the clutch and simultaneously engaging the brake to stop the spindle during continued movement of the segment and continued rotation of the drive shaft and for thus interrupting the reverse rotation of the spindle to provide a period of dwell during which the spindle is stationary, and means for causing said interrupting means to act so as to provide said period of dwell after an initial reverse rotation of the spindle and prior to a final reverse rotation thereof so that said final reverse rotation is stopped at said starting position independently of the clutch and as determined by said shoulder and abutment.

3. A spring winding machine comprising in combination,

tion, a spindle having two alternative predetermined starting positions one corresponding to rotation in one winding direction and the other corresponding to rotation in the opposite winding direction, means connected with the spindle for rotation therewith and constructed for engaging a wire to be wound, means including a pair of alternatively useable shoulders rotatable with the spindle and a pair of alternatively useable abutments cooperating respectively with said shoulders for stopping reverse rotation of the spindle in one or the other of its respectively corresponding starting positions, a gear segment oscillated through a predetermined angle, a drive shaft connected with the segment for rotation thereby first in one direction and then reversely during each segment oscillation, means including a clutch interposed between said drive shaft and said spindle for effecting rotation of the spindle in either winding direction from its corresponding starting position to effect winding of the wire to form a spring and for then effecting rotation of the spindle in the direction reverse of the selected winding direction to its said corresponding starting position, means operable in conjunction with said pairs of shoulders and said pairs of abutments for moving one of said pairs relatively to the other to prevent interengagement of said shoulders and abutments during rotation of the spindle in either winding direction and during the initial rotation of the spindle in the corresponding reverse direction, and means for interrupting the action of the clutch and for thus interrupting the reverse rotation of the spindle in the last said direction during continued rotation of the drive shaft so as to provide a period of dwell during which the spindle is stationary, and means for causing said interrupting means to act so as to provide said period of dwell after an initial reverse rotation of the spindle and prior to a final reverse rotation thereof so that said final reverse rotation is stopped at said starting position independently of the clutch and as determined by the shoulder and abutment corresponding to the last said direction of reverse rotation.

4. A spring winding machine comprising in combination, two rotatable spindles having predetermined starting positions, two means connected respectively with the spindles for rotation therewith and constructed respectively to engage wires to be wound, two drive shafts, a single power means connected with the drive shafts for rotating them successively and in unison to predetermined extents in winding directions and then to the same extents in reverse directions, two electromagnetic clutches each serving when engaged to connect one spindle with the corresponding drive shaft for rotation therewith, two electromagnetic brakes each serving when engaged to stop

one spindle, a single cam means connected with the power means for the drive shafts and rotatable through one revolution during each cycle of winding and reverse rotations of said drive shafts, two means each including electrical circuits and including switches operable by said single cam means and each constructed and arranged to serve upon operation of its said switches for disengaging the corresponding brake and simultaneously engaging the corresponding clutch near the beginning of each rotation of the corresponding drive shaft in the winding direction to start rotation of the corresponding spindle in the winding direction from its said starting position to effect winding of the corresponding wires to form a spring, each of the last said means being also constructed and arranged to maintain the corresponding clutch engaged and the corresponding brake disengaged until after the next following reverse rotations of the corresponding drive shaft has started, two cams each rotatable in unison with the rotation of a corresponding spindle in the winding and reverse directions, and two means each including electrical circuits and including switches operable by a corresponding cam during each reverse rotation of the corresponding spindle for disengaging the corresponding clutch and simultaneously engaging the corresponding brake to stop the corresponding spindle at least approximately in its said starting position.
